[57] CLAIM

The ornamental design for a flexible container, as shown and described.

DESCRIPTION

FIG. 1 is a perspective view of a first embodiment of the flexible container showing our new design;

FIG. 2 is a front elevational view thereof, the rear elevational view being omitted because it is a mirror image of FIG. 2; FIG. 3 is a right side elevational view thereof, the left side elevational view being omitted because it is a mirror image of FIG. 3;

FIG. 4 is a top plan view thereof;

FIG. 5 is a bottom plan view thereof;

FIG. 6 is a perspective view of a second embodiment of the flexible container showing our new design;

FIG. 7 is a front elevational view thereof, the rear elevational view being omitted because it is a mirror image of FIG. 7; FIG. 8 is a right side elevational view thereof, the left side elevational view being omitted because it is a mirror image of FIG. 8;

FIG. 9 is a top plan view thereof; and,

FIG. 10 is a bottom plan view thereof.
